UNITED STATES PATENT OFFICE.

GEORGE C. DRESSEL, OF NEW YORK, N. Y.

DESIGN FOR A LANTERN.

SPECIFICATION forming part of Design No. 22,854, dated October 24, 1893.

Application filed September 14, 1893. Serial No. 485,510. Term of patent 7 years.

To all whom it may concern:

Be it known that I, GEORGE C. DRESSEL, a citizen of the United States, residing at New York, county and State of New York, have 5 invented and produced a new and original Design for Lanterns, of which the following is a specification, reference being had to the accompanying drawing, which represents a perspective view thereof.

10 This invention relates to a new and original design for lanterns and more particularly to the headlights of motors.

The leading feature of my design consists 15 of a lantern having a top made with concavo convex sides, concavo convex ends and with a circular dome.

a, represents the top plate of a lantern *A* made in the form of a trough, with rounded top and concavo convex sides. The ends *b*, slant outwardly from top to bottom and are 20 also concavo convex. From the center of plate *a*, projects upwardly the contracted neck *c*, of the circular dome *d*.

What I claim is—

The design for a lantern, as herein shown 25 and described.

GEO. C. DRESSEL.
